WO WO DM/093190 3/2017

Primary Examiner — Susan Bennett Hattan*Assistant Examiner* — Suzanne E Tisdell(74) *Attorney, Agent, or Firm* — Crowell & Moring LLP(57) **CLAIM**

The ornamental design for a hood for a vehicle, as shown and described.

DESCRIPTION

This application contains subject matter related to the following co-pending U.S. design patent applications:
Application Ser. No. 29/579,103, filed Sep. 28, 2016 and entitled “Hood for a Vehicle”; and
Application Ser. No. 29/605,288, filed herewith and entitled “Vehicle, Toy, and/or Replicas Thereof”.

FIG. 1 is a top view of a hood for a vehicle according to the design;

FIG. 2 is a top, right, front perspective view thereof;

FIG. 3 is a front view thereof;

FIG. 4 is a right side view thereof, the left side view being mirror symmetrical;

FIG. 5 is a bottom view thereof;

FIG. 6 is a rear view thereof; and,

FIG. 7 is a bottom, left, front perspective view thereof.

1 Claim, 7 Drawing Sheets(56)
